UNITED STATES PATENT OFFICE.

JOHN C. BARBER, OF CHICAGO, ILLINOIS.

CENTER-PLATE FOR CAR-TRUCKS.

SPECIFICATION forming part of Letters Patent No. 886,247, dated November 12, 1901.

Application filed June 8, 1901. Serial No. 62,819. (No model.)

To all whom it may concern:

Be it known that I, JOHN C. BARBER, a citizen of the United States, residing at Chicago, in the county of Cook and State of Illinois, have invented certain new and useful Improvements in Center-Plates for Car-Trucks; and I do hereby declare the following to be a full, clear, and exact description of the invention, such as will enable others skilled in the art to which it appertains to make and use the same.

My invention has for its object to provide an improved center-plate for car-trucks and other uses.

15 To this end my invention consists of the novel devices and combinations of devices hereinafter described, and defined in the claims.

The invention is illustrated in the accompanying drawings, wherein like notations refer to like parts throughout the several views.

Figure 1 is a view showing the center-plate in elevation and the bolsters in cross-section, with some portions broken away. Fig. 2 is a 25 plan view of the bottom member of the center-plate detached. Fig. 3 is a view in cross-section through the center-plate and bolsters on the line $x^3 x^3$ of Figs. 2 and 4, with the parts in working position; and Fig. 4 is a 30 plan view of the top or upper member of the center-plate detached.

The bottom member of the center-plate is of such construction as to afford base-flanges a , by which the plate is secured to the truck-bolster, shown as made up of I-beams 1, by means of bolts 2 passing through the said flanges of the plate and the outer flanges of the I-beams 1. (Shown in Fig. 2.) The bottom member of said center-plate is also of 35 such construction as to afford a raised bearing-surface a' , of convex form, on its face. This body or bearing portion a' of the lower member is provided with a hub-seat a^2 , surrounding the center-pin passage, and is also 40 provided with a series of radial grooves or channels a^3 , extending outward from points near the hub-seat a^2 to the junction of the raised body with the flat flanges a of the plate, thereby affording clearing-channels, which 45 are open at their outer end. The lower member of the center-plate is also provided with raised segmental flanges a^4 for coöperation

with the hub-seat a^2 to take the buffing strains or forward and backward strains from the upper member of the two center-plates. 55

The upper member of the two center-plates is of such construction as to afford a downwardly-extended hub b for working in the hub-seat a^2 of the lower member, as best shown in Fig. 3, and to afford a concave bearing surface or face b' for coöperation with the raised or convex bearing-surface a' of the lower member. The upper member is also provided with the extended horizontal flanges b^2 , by which the same is bolted to the body-bolster 3 of the car. The upper member is provided with raised flanges b^3 , adapted to receive and embrace the said body-bolster 3. 60

When the parts are in working position, as shown in Figs. 1 and 3, it is obvious that the two plates are pivotally connected by their coöperating hub and hub-seat, and in practice would also be connected to the car and to the car-body by a center-pin. (Not shown.) 70

The forward and backward thrusts or buffing strains will be taken from the hub and outer edges of the upper plate onto the hub-seat and the raised flanges a^4 of the lower plate. The raised flanges a^4 therefore reinforce and relieve the hub and hub-seat from 75 a large part of the buffing strains, and thereby greatly increase the strength and durability of the center-plate.

In view of the convex form of the bearing surface or face of the lower member and the 80 radial channels or grooves a^3 provided therein it follows that water, rust, dust, or other sediment cannot accumulate between the bearing-surfaces of the two coöperating members making up the center-plate. Water of course will be shed from the lower member owing to the convex form of the bearing-surface, and any dust, rust, dirt, or other sediment which might otherwise accumulate 85 thereon will be worked out through the channels a^3 under the swiveling movement of the two members with respect to each other. The radial channels insure a clearing action for the reason that said channels will catch the sediment under the swiveling movement of the two members in respect to each other and permit said sediment to move radially outward and downward without being clamped 90 between the bearing-surfaces. 95

Center-plates constructed as above described will last much longer, give better service, and work much better without lubrication. In the old or standard form of center-
 5 plates the bottom member has a concave face and the upper member a convex face, which makes the bottom member a catch-basin for water and sediment of all sorts. Hence the bearing-surfaces rapidly rust, and the accum-
 10ulating rust, sand, and other sediment grind the bearing-surfaces under the swiveling motion of the plates, thereby greatly shortening the life of the center-plate in the service. This serious defect is entirely over-
 15 come by my invention, as above described.

As another feature of large advantage this improved center-plate is better adapted for use on the type of truck-bolster now coming into most general use. The prevailing tendency in car-truck construction is to substitute metallic for wooden parts. Metallic bolsters are now most generally embodied in all new rolling-stock. These metallic bolsters are usually made up of standard structural forms, such as the channel, angle-iron, or I-beam forms. The I-beams are the form most generally employed, and have been shown in Figs. 1 and 3 of the drawings. These I-beams are usually so set that their inner or
 20 facing flanges do not meet, but stand spaced apart from each other throughout the central portion of the bolster or at the place where the center-pin would pass through the members of the center-plate. The lower member of the center-plate must therefore span or bridge this opening between the I-beam flanges of the truck-bolster, and when the load is taken at the center of the center-plate, as in the old form, breakage is likely to occur.
 25
 30
 35
 40

Otherwise stated, the old form of center-plate is not well adapted to this bridging action, because it is weak and unsupported from below at the point of the greatest strain.

With my improved form of center-plate,
 45 hereinbefore described, the body or main por-

tion of the bearing-surface is radially outward of the hub and the hub-seat connecting the two plates, and hence the strain is taken on parts of the lower member which directly overlie and are supported by the flanges of the I-beams 1 making up the truck-bolster. This improved center-plate is therefore well adapted for use with metallic truck-bolsters made up of the standard structural forms—such as I-beams, channels, or angle-beams—now most generally employed.

It will be understood that the construction might be changed in detail without departing from the spirit of the invention.

What I claim, and desire to secure by Letters Patent of the United States, is as follows:

1. A center-bearing plate composed of an upper and lower member connected for swiveling movement in respect to each other, the upper member having a concave bearing-surface, and the lower member having a convex bearing-surface, at least one of said bearing-surfaces having radial clearing-grooves, whereby water, dust, rust or other form of materials cannot accumulate between the bearing-surfaces of the two plates, but will be worked off and out through said clearing-grooves, substantially as described.

2. A center-plate composed of an upper and a lower member connected for swiveling movement in respect to each other, the upper member having a concave bearing-face and the lower member having a convex bearing-face provided with radial clearing-grooves, whereby water, dust, rust or other foreign materials cannot accumulate between the bearing-surfaces of the two plates but will be worked off and out through said clearing-grooves, substantially as described.

In testimony whereof I affix my signature in presence of two witnesses.

JOHN C. BARBER.

Witnesses:

JAS. F. WILLIAMSON,
 F. D. MERCHANT.
